United States Patent Office.

L. E. TRUESDELL, OF CHICAGO, ILLINOIS.

Letters Patent No. 76,558, dated April 7, 1868.

IMPROVEMENT IN BRIDGES.

The Schedule referred to in these Letters Patent and making part of the same.

TO ALL WHOM IT MAY CONCERN:

Be it known that I, L. E. TRUESDELL, of Chicago, in the county of Cook, and State of Illinois, have invented a new and useful Improvement in Iron Bridges; and I do hereby declare the following to be a full and exact description thereof, reference being had to the accompanying drawings, and to the letters of reference marked thereon, making a part of this specification, in which—

Figure 1 is side elevation of my invention.

Figure 2 is a vertical transverse section through the same.

Figure 3 is a vertical section through one of the posts on line *e e*, showing the manner of connecting its corresponding parts.

Figure 4 is a transverse section of one of the posts on lines *x x*, showing the manner of connecting the bars which form the lower chord.

Figure 5 is a detached section of a portion of the arch-cap on line *ff*, showing the manner of holding the outer ends of the ties.

Figure 6 is a vertical transverse section through the cap on line *d d*, showing the shape thereof.

Similar letters of reference, as they occur in the separate figures, denote like parts in both of the drawings.

My invention relates to an improvement in that class of bridges which is constructed of iron; and the nature of my improvement consists,

First, in the shape of the caps and posts, as will be hereinafter more fully explained.

Second, in the manner of connecting the several parts one to the other, whereby great strength and durability are obtained at a much less expense than any of the heretofore-known arrangements.

To enable others skilled in the art to more fully understand and construct my invention, I will proceed to describe the same with reference to the drawings.

A and A" represent the caps or upper beam of the bridge. The latter is constructed in a circular form laterally, and provided with projections or flanges extending upward and downward from the centre, whereby great strength is obtained. The former cap, A, is constructed in a like manner, laterally, and slightly curved, or arched longitudinally, and is hinged or jointed at the lower end to clamp-plates D D, that hold the outer ends of the bars which form the lower chords C and C". Said caps extend obliquely upward, and pass into mortises cut in and through the upper ends of posts B B, and are there connected to caps A" by means of a lock or dove-tail joint, as shown in the drawings by fig. 3. Said posts extend downward to a distance sufficient to bring the lower ends thereof in a horizontal line with the lower end of clamp-plates D D, and are provided with slots cut therein, in the direction of the length of the bridge, for the reception of chords C and C", the parts of said posts protruding downward. Each side of said slots is fluted, or provided with a series of vertical corrugations, which correspond with and take into a like series of corrugations in the end of the bars which form chords C and C", as the ends of the same are lapped or placed together within said slots, and are held therein by means of key *i*", passing through mortises cut in said posts at right angles with said slots, said key coming in contact with and against an adjustable slide, E", forcing the same upward against said bars, thus firmly connecting the same the entire length of the bridge.

The lower side of caps A and A" is provided at the joint thereof, and within the mortises in said posts, with a series of corrugations, cut therein transversely, which receives the ends of ties S and S". The ends thereof are slightly curved, and also corrugated, corresponding one with the other, and are held together and within the corrugations in said caps by means of slide E passing through the mortise in said post under the ties. Said slide is also corrugated, agreeing with the corrugations in said ties, and is capable of vertical adjustment by means of key *i* passing through a mortise cut through said posts at right angles with and under said slide, thus forcing the same upward, which firmly connects the several parts one to the other.

Ties S and S" extend obliquely downward, and are connected to the lower end of the posts in a like manner as shown by fig. 3. That portion of the posts between the slots is also corrugated, which receives the corrugated part of the ties, and is held together by means of slide E", which is also fluted, and forced upward by key *i*". Thus the entire structure is firmly connected together. The ends of the outer ties S" S" are held

within a bevelled corrugated clamp-plate, H H, which is held within a corresponding mortise cut through the centre of cap A, as shown by fig. 5.

The sides of the bridge are connected laterally by means of sills P passing across from post to post, as shown by fig. 2. The floor F is supported by means of joist T resting upon chords C and C'.

Posts B B are constructed with four flanges, as shown at L, fig. 3, and slightly tapered from the centre upward and downward, nearly to that portion of post through which the mortises are cut, and are there enlarged to give the necessary strength.

The object of this style of post is to give greater strength with less heft of iron, as the flanges act as a brace one for the other.

Having thus described the nature and object of my invention, what I claim as new, and desire to secure by Letters Patent, is—

1. The construction and arrangement of the corrugated clamp-plates H, in combination with the tie-rods S', in the manner and for the purpose herein described.

2. The construction and arrangement of the caps A and A'' and posts B of a bridge so that the suspension-rods may be clamped together by means of the corrugations upon the ends of the same, and held firmly in position by means of clamp E and wedge or key i, substantially in the manner and for the purpose herein described.

L. E. TRUESELL.
